UNITED STATES PATENT OFFICE

162,371

STARCH PAN OR THE LIKE

George A. Bauer, Milwaukee, Wis.

Application November 19, 1948, Serial No. 149,710

Term of patent 14 years

(Cl. D44—9)

To all whom it may concern:

Be it known that I, George A. Bauer, a citizen of the United States, residing at Milwaukee, in the county of Milwaukee and State of Wisconsin, have invented a new, original, and ornamental Design for Starch Pan or the like, of which the following is a specification, reference being had to the accompanying drawing, forming part thereof.

Figure 1 is a side elevational view of a starch pan or the like, showing my new design.

Figure 2 is a rear elevational view.

Figure 3 is a top plan view.

Figure 4 is a bottom plan view.

Figure 5 is a front elevational view thereof.

I claim:

The ornamental design for a starch pan or the like, as shown.

GEORGE A. BAUER.
